CLAIM

The ornamental design for an electronic whistle type alarm, as shown and described.

DESCRIPTION

FIG. 1 is a perspective view of an electronic whistle type alarm;

FIG. 2 is a front elevation thereof;

FIG. 3 is a rear elevation thereof;

FIG. 4 is a left side elevation thereof;

FIG. 5 is a ride side elevation thereof;

FIG. 6 is a top plan view thereof; and,

FIG. 7 is a bottom view thereof.

The broken lines bisecting the whistle carrying cord are for the purpose of illustrating indeterminate length.
